CLAIM

The ornamental design for element for ski pole handle
or similar article, as shown and described.

DESCRIPTION

FIG. 1 is a side elevational view of an element for ski
pole handle or similar article showing my new design;
FIG. 2 is a side elevational view of the side opposite
that shown in FIG. 1;
FIG. 3 is a top plan view thereof;
FIG. 4 is a bottom plan view thereof;
FIG. 5 is an end elevational view thereof; and,
FIG. 6 is an end elevational view opposite that shown in
FIG. 5.
